UNITED STATES PATENT OFFICE

IRA D. TRAVIS, OF SALT LAKE CITY, UTAH

CASTING MACHINE

Application filed June 15, 1928. Serial No. 285,731.

My invention relates to permanent molds, and has for its object to provide a new and efficient mold for casting railway brake shoes. A further object is to provide a mold which 5 will simplify and cheapen the production of odd and unusual shaped castings and automatically eliminate them when they are finished.

A still further object is to provide a mold 10 of two complementary parts, one stationary and the other movable, each of which is equipped with an automatic extractor for releasing the product when completed, and which mold can be opened, closed and 15 adjusted to the exigencies of the casting operation by fluid pressure.

A still further object is to provide a brake 20 shoe casting machine which will be economical in construction, efficient in operation, and which will take precedence over the present process of sand casting.

These objects I accomplish with the device 25 illustrated in the accompanying drawings, in which similar numerals and letters of reference indicate like parts throughout the several views and as described in the specification forming a part of this application and pointed out in the appended claims.

In the drawings, in which I have shown 30 the best and most preferred manner of building my invention, Figure 1 is a side elevation of my machine with the molds separated. Figure 2 is a plan view of the same. Figure 3 is a side elevation of the machine with the 35 molds together for pouring. Figure 4 is a front view of a section of one side of the mold, showing the position of the extractors and the general shape of the form therein. Figure 5 is a view of the complementary mold. 40 Figure 6 is a side view of one of the extractors. Figure 7 is a side view of a modified form of constructing the same. Figure 8 is a diagrammatic side view of one form of 45 making the machine, showing the molds adapted to be tilted for placing cores therein and for the more convenient cleaning of the face of the molds and the forms therein. Figure 9 is a front face view of a modified 50 form of constructing the molds for a series of forms, parts cut away. Figure 10 is the

complementary mold. Figure 11 is a section on line 11—11 of Figure 5. Figure 12 is a section on line 12—12 of Figure 4. Figure 13 is a section on line 13—13 of Figure 3.

The mold comprises two complementary sections, each of which is provided with one or more protrusions on its front face. These are so situated that they face depressions of similar shape and size in the opposite section of the mold, so that when the mold is closed the protrusions of one portion fit into the depressions of the other, forming a block within which the form for the casting is situated, with the lower side of the depressions and protrusions forming the top face of the form in which the casting is made. These protrusions, in turn, are made up of two quite unequal elements each, one stationary with respect to its section of the mold and the other movable therein. The first is the larger of the two and furnishes the bearing that supports the shaft of the eliminating device, while the other is an essential part of the extractor proper. Thus it is evident 70 that, although these protrusions are integral parts of the molds, their primary function is to provide for the automatic removal of the finished castings.

In the drawings I have shown the frame so upon which my machine is mounted as A, with the fluid operated cylinder as B, and the two separate molds as C and D. A piston rod E connects the back side of the mold D with the fluid cylinder by which the mold 85 D is moved to contact with and away from the mold C. Both of the molds are provided with support blocks 1 and 2 on each side thereof, with a portion of each block cut and curved and on which blocks the molds are supported on the frame, either when upright or tilted to be cleaned.

Each of the molds C and D are provided with depressions on the front face thereof and each is also provided with protrusions, 90 so that when placed together the protrusions in the one mold fit into the depressions of the opposite mold. The two molds, when placed together, form the cavity into which the molten metal is poured to make the cast- 100

ing. The stationary mold C is provided with a single protrusion 5 on the front face thereof, and the movable mold D is provided with protrusions 6 and 7 adapted to engage with the protrusion 5 on each side thereof to form a block when fitted together. The form 8, into which the molten metal is poured, is made half in each mold with the lower side 9^a of the protrusions 5, 6 and 7, when placed together, forming the top of the form, and with the mold D surrounding and comprising most of the form for the casting, with only half of the ends, half of the bottom of the form, one side and a part of the top, being in the mold C, and with the balance of the form being in the mold D. The shape of the castings made may vary from that shown in the drawings, but the protrusions on each mold will be present in all cases.

This construction of the molds facilitates the automatic expulsion of the casting therefrom, which is accomplished by two spaced apart extractors 9 and 10 in the mold D and one extractor 11 in the mold C for every casting form made in each. Obviously each individual mold may contain several forms, thus making possible the production of a number of castings at each pouring. The extractors 9 and 10, and 11 are made, as shown in the drawings, with tapered shaft 12, having an enlarged semi-spherical head 13 on the inner end thereof and a nut 14 on the outer end. These shafts pass through holes in molds C and D and are so placed that the heads 13 fit into the semi-spherical depressions 16 in the side walls of form 8 when the molds are closed for pouring. When in that position the back side of the head 13 forms a small portion of the wall of the mold cavity. A modified form of the extractor may be made with a conical head 13^a, as shown in Figure 7, adapted to fit into a conical shaped depression within the molds C and D. As may be seen, the shape of the tapered shaft 12 may vary from being tapered slightly to having the end 13^a tapered and the balance of the shaft cylindrical. The nut 14 on the end of the shaft 12 is provided so that when the mold D is moved from the mold C the mold will slide on the shafts 12 until the head or nut 14 comes into contact with the back side of the mold, which action will draw the heads 13 from the depressions 16 in the side walls of the form 8, drawing the finished casting therefrom, and the shafts 12 are susceptible of being so adjusted that the distance between the heads 13 will be greater than the width of the casting, thus insuring its complete release the moment it is withdrawn from the mold cavity.

When the mold D is brought into contact with the mold C, the heads 13 fit into the depressions 16 in the form 8, and the form is ready for pouring. Pouring gates 17 are provided in the molds, half in each mold,

with lateral holes 18 leading to the different forms in the molds through which the molten metal is poured to form the castings. The molds shown in Figures 1, 2, 3, 4 and 5 of the drawings are for two castings only, but it will be obvious that more castings could be made in each mold, as shown by Figure 6 of the drawings, in which more forms are shown.

Having thus described my invention, I desire to secure by Letters Patent and claim:

1. In a casting machine the combination of a frame having a fluid cylinder mounted on one end thereof, and a stationary mold section mounted on the other end; a movable mold section mounted between said cylinder and said stationary mold section, adapted to be moved to and from said stationary mold section by a piston rod operated by said cylinder; protrusions on said movable mold section; depressions in said stationary mold section adapted to be partially filled by said protrusions on the movable mold section with the rest of the space hollow to be filled by molten metal to form a casting; and extractors in said stationary mold section adapted to be moved by said movable mold section and to force the finished casting from the stationary mold section.

2. In a casting machine the combination of two mold sections, one stationary and the other movable, with a depression in the stationary mold section and a depression formed and a protrusion in the movable mold section, said protrusion adapted to fit into said depression in said movable mold section to partially fill it and thus make the rest of a form for casting with the majority of it in the movable mold section; and spaced apart extractors carried within said mold sections adapted to be actuated by the movable mold section and to force the finished casting from the form in said stationary mold section.

3. In a casting machine the combination of two complementary mold sections, one of which is stationary and the other movable, with depressions and protrusions formed on the engaging faces of both mold sections; extractors mounted through said protrusions and with the end of said protrusions being formed by said extractors, with the protrusions fitting into similarly shaped depressions in the complementary mold sections, said extractors adapted to be actuated by the movement of the movable mold sections to draw the finished castings from the mold sections; and forms made in each mold section in which the molten metal is poured to produce the casting.

4. In a casting machine the combination of two complementary mold sections having depressions and protrusions formed on the front faces thereof, said depressions adapted to receive said protrusions when the mold

sections are together; extractors mounted through said mold sections forming part of the protrusions and having the head thereof fitting into part of the depressions; and nuts 5 formed on the back side of said extractors adapted to actuate said extractors when the movable mold section comes into contact therewith.

5. In a casting machine the combination of 10 complementary mold sections having depressions and protrusions formed on the engaging faces thereof, with extractors forming part of the protrusions and fitting into said depressions, and with the bottom face of 15 said depressions and protrusions forming the top side of the form into which the molten metal is poured to form the casting.

6. In a device of the class described the combination of two complementary mold 20 sections; depressions and protrusions formed on the engaging faces thereof, with the depression of one mold section fitting into and filling the depression of the complementary mold section, and with the bottom face of said 25 depressions and protrusions forming the top side of the form in which the casting is made; extractors carried in said protrusions with the heads thereof semi-spherical and fitting into similarly shaped depressions in the 30 complementary mold section; a form made in said mold sections, having the major portion thereof formed in the movable mold section, into which the molten metal is poured to make the castings.

35 7. In a casting machine the combination of two complementary mold sections, one of which is movable and the other stationary, but adapted to be tilted; depressions and protrusions formed on the front faces of both 40 mold sections; extractors mounted through said protrusions; semi-spherical heads on said extractors adapted to fit into similarly shaped depressions in the complementary mold section; and means to actuate said extractors by the movement of the movable mold 45 section.

8. In a casting machine the combination of 50 two complementary mold sections; extractors mounted through said mold sections to withdraw the finished castings when the mold sections are separated, said extractors having the shafts thereof tapered and the heads semi-spherical in shape, with the heads adapted to fit into similarly shaped depressions in the 55 complementary mold section.

9. In a casting machine the combination of 60 two complementary mold sections, one stationary and the other longitudinally movable, each with compound depressions and protrusions, the protrusions of the movable mold section being adapted to fit into and partially fill the depressions in the stationary mold section, providing the rest of the form for casting with the majority of the form in 65 the movable mold section; means to auto-

matically extract the finished casting and means to actuate the movable mold section.

In testimony whereof I have affixed my signature.
